[57] CLAIM

The ornamental design for a push bumper with side guards for mounting to a bumper of a car, as shown and described.

DESCRIPTION

FIG. 1 is a front perspective view of a push bumper with side guards for mounting to a bumper of a car, showing my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a left side elevational view thereof;

FIG. 7 is a left side elevational view thereof with the rear mounting parts removed for ease of disclosure; and,

FIG. 8 is a right side elevational view thereof with the rear mounting parts removed for ease of disclosure.
